UNITED STATES PATENT OFFICE.

JOHN L. RUSHTON, OF MUSCATINE, IOWA.

SAW-GUARD.

1,154,209.

Specification of Letters Patent. Patented Sept. 21, 1915.

Application filed August 11, 1914. Serial No. 856,294.

To all whom it may concern:

Be it known that I, JOHN L. RUSHTON, a citizen of the United States, residing at Muscatine, in the county of Muscatine and 5 State of Iowa, have invented certain new and useful Improvements in Saw-Guards, of which the following is a specification.

This invention relates to an improved saw guard which is intended to be used in connection with circular saws, and the principal object of the invention is to provide a saw guard which will completely cover the saw, thus preventing danger of the operator being cut, the guard being so constructed 15 that it may be used when sawing lumber of any thickness through which the saw will pass.

Another object of the invention is to so mount the guard that it may slide longitudinally on its frame or track when a piece of lumber is being cut, a spring being provided to return the guard to its normal position after a board has been cut and yieldably hold the guard in the position to cover the 25 saw.

This invention is illustrated in the accompanying drawings, wherein:

Figure 1 is a view in elevation showing the guard in place. Fig. 2 is a top plan view 30 of the guard. Fig. 3 is a longitudinal sectional view through the guard taken along the line 3—3 of Fig. 2. Fig. 4 is a transverse sectional view taken along the line 4—4 of Fig. 3. Fig. 5 is a fragmentary sectional view showing the manner of slidably connecting the guard with the track, and also the manner of slidably connecting the sections of the guard.

The main tracks 10 and 11 have their rear 40 end portions bent to form standards 12 and 13, which terminate in feet 14 and 15 which are secured to the underface of the sawing table 16 by the bolts or other fasteners 17. It will thus be seen that the main tracks 45 will be suspended in spaced relation above the sawing table and that the tracks extend upon opposite sides of the circular saw 18, which is rotatably mounted by means of its driving shaft 19 and extends through the 50 slot 20 formed in the sawing table. To the side flanges of the main tracks there have been secured strips of angle iron forming auxiliary track sections 21 and 22, which are positioned in spaced relation to the main 55 track sections, thus leaving space between

the same, as shown clearly in Figs. 3, 4 and 5.

The guard or housing, which is intended to inclose the saw, is slidably carried by the track and comprises the upper and lower 60 side sections 23 and 24 and intermediate side sections 25 and 26, the upper side sections being connected by the cross bar 27, which engages the longitudinally extending bar 28 carried by the end wall 29 of the housing. 65 The cross bar 27 and the longitudinally extending bar 28 carry angle strips 30 and 31 which fit into the spaces between the main track sections and auxiliary track sections, as shown in Figs. 4 and 5, thus suspending 70 the housing and permitting the housing to be moved longitudinally. In order to yieldably hold the housing in the normal position, there is provided a strong spring 32 which has one end portion connected with 75 the eye 33 carried by the longitudinally extending bar 28, and has its opposite end portion connected with the eye 34 carried by the block or bridge 35 which connects the free ends of the track sections. The rear 80 end portions of these tracks are connected by the bracing bridge 36, as shown clearly in Fig. 2, and it will thus be seen that these tracks will be securely held at the desired distance apart to permit the housing to slide 85 easily without any danger of the supporting strips 30 and 31 slipping from between the track sections.

The side sections 23, 25 and 26 of the housing each carries a strip 37 which has its side 90 portions bent to form flanges 38 positioned in space relation to the strip. The sections 25, 26 and 24 each has a strip 39 secured to its upper face, which has its side portions bent to form overhanging flanges which 95 form pockets 40 in which the flanges 38 of the strips 37 fit, thus slidably connecting the side sections of the housing and permitting the side sections to move independently without becoming disconnected. It will be 100 noted, however, that when one set of side sections is moved longitudinally by a board which is being cut, the end wall 29 will be moved, thus expanding the spring. The end wall and the longitudinally extending bar 105 28 will thus be moved to the position indicated by dotted lines in Fig. 1 without the remainder of the housing being removed from about the saw. Therefore, the upper portion of the saw which extends through 110

the board will not be exposed, and therefore there is no danger of the operator being cut by the saw.

When this device is in use, it is mounted 5 as shown clearly in the drawings, and the piece of lumber which is to be cut is placed upon the cutting table 16 and moved toward the saw from the open end of the housing. As the piece of lumber reaches the housing, 10 it will engage one or more of the side sections of the housing and will cause either the entire housing or only the lower portion thereof together with the rear wall to be moved to the position indicated by the 15 dotted lines in Fig. 1, thus permitting the saw to cut the board. After the board has been cut, the pieces will be withdrawn from the housing by a transverse movement and the spring will then return the housing to 20 the normal position. I have thus provided a saw guard which will completely cover the saw, thus preventing any danger whatever of the operator being cut when the saw is in use, and also when the saw is 25 running but not in use.

What is claimed is:

1. The combination of a sawing table, tracks extending above said table and in spaced relation thereto, a housing slidably 30 carried by said tracks, said housing comprising side walls formed of a plurality of slidably connected sections positioned in superposed relation, an end wall for said housing, a longitudinally extending bar carried by said end wall and resting upon the inner end portions of the upper sections of 35 said side walls, a cross bar connecting the forward end portions of the upper sections of said side walls, and resilient means connecting said longitudinally extending bar with the forward end portions of said track 40 to yieldably hold said housing in a normal position.

2. A saw guard comprising tracks, a housing 45 slidably connected with said tracks, said housing comprising side walls formed of sections positioned in superposed relation and slidably connected, a cross bar connecting the forward end portions of said side 50 walls, a rear wall, a longitudinally extending bar carried by said rear wall and resting upon the inner end portions of said side walls and engaging said cross bar, and resilient means having one end portion connected with said longitudinally extending 55 bar and its opposite end portion connected

with said tracks to yieldably hold said housing in a normal position, the sections of said side walls having independent sliding movement with respect to the ones above them 60 and carrying with them said rear wall and longitudinally extending bar.

3. A saw guard comprising supporting tracks, a housing slidably connected with said tracks and comprising side walls 65 formed of a plurality of slidably connected sections positioned in superposed relation, an end wall engaging said side walls and moving with said side walls, and means for yieldably holding said housing in a normal 70 position.

4. In a saw guard, a housing comprising side walls formed of a plurality of slidably connected sections, a rear wall, a cover formed of forward and rear sections, the 75 forward cover section being secured to the upper sections of the side walls and the rear cover section being secured to said rear wall and slidably engaging the upper sections of 80 said side walls, means for slidably mounting said housing, and means for yieldably holding said housing in a normal position.

5. A saw guard including a housing comprising side walls formed of a plurality of sections positioned in superposed relations, 85 means for slidably connecting the sections of each side wall, a rear wall for said housing moving with a selected set of the sections of said side walls, means for slidably mounting said housing and means connected 90 with said rear wall for yieldably holding said housing in a normal position.

6. A saw guard comprising a track, a bar slidably connected with said track, resilient means connected with said track and with 95 said cross bar for yieldably holding said cross bar in a normal position, a rear wall connected with said cross bar, side walls comprising a plurality of slidably connected sections having their inner ends engaging 100 said rear wall, a cross bar connecting the upper sections of said side walls and engaging said first mentioned cross bar, and means for slidably connecting said second mentioned cross bar with said track. 105

In testimony whereof I affix my signature in presence of two witnesses.

JOHN L. RUSHTON.
